UNITED STATES PATENT OFFICE.

ANTHONY L. STEBOR, JR., OF PLAINFIELD, NEW JERSEY.

SHOE-PROTECTOR.

1,326,542.

Specification of Letters Patent. Patented Dec. 30, 1919.

Application filed August 20, 1918. Serial No. 250,702.

To all whom it may concern:

Be it known that I, ANTHONY L. STEBOR, Jr., a citizen of the United States, residing at Plainfield, in the county of Union, State 5 of New Jersey, have invented certain new and useful Improvements in Shoe-Protectors; and I do hereby declare the following to be a full, clear, and exact description of the invention, such as will enable others 10 skilled in the art to which it appertains to make and use the same.

This invention relates to improvements in protectors for the tips of shoes.

One object of the present invention is to 15 provide a novel and improved device which can be worked on the toe of a shoe for the purpose of protecting the same from wear, especially when used by bootblacks, chauf- feurs, or other persons whose work entails 20 the rubbing of the toes of the shoes.

Another object is to provide a novel and efficient device of this character wherein the composition is such as to insure great protection to the shoe and at the same time be 25 subject to very little wear of itself.

Other objects and advantages will be apparent from the following description when taken in connection with the accompanying drawing.

30 In the drawing:

Figure 1 is a perspective view of my improved shoe tip protector, the same being shown in connection with a shoe which is in dotted lines.

35 Fig. 2 is an enlarged vertical longitudinal sectional view through the protector.

Fig. 3 is a vertical transverse sectional view through the shoe tip covering portion of the device.

40 Referring particularly to the accompanying drawing 10 represents a hollow member which is formed to fit snugly over the toe portion of the shoe of the wearer. En- circling the shoe and passing over the in-

45 step thereof, and beneath the arch, is a strap 11. Connected to the rear edges of the sides

of the member 10 are the longer straps 12 and 13, each being secured to the strap 11 where it intersects or crosses said strap. The other end of the strap 12 is provided 50 with a buckle 14 for engagement by the end of the other strap 13, said straps being engaged around the shoe and buckled together back of the heel. A third short strap 15 is secured at one end to the upper rear 55 edge of the tip protector and at its other end to the strap 11.

The member 10 is preferably formed from rubber, fabric, and woven wire, as clearly seen in Figs. 2 and 3 of the drawing. In 60 these figures there is shown an outer layer of rubber which forms the crown of the device, the edges of which are turned inwardly beneath the sole of the shoe, as shown at 16, the said rubber being designated by the 65 character 17. Disposed beneath the sole of the shoe is a piece of woven wire the edges of which are turned upwardly and embedded in the marginal edges of the rubber layer 17. This wire is covered, outwardly with a 70 rubberized cloth, and within, or where the sole of the shoe rests, is a layer of rubber 18. A fabric 19 is embedded in the first-named rubber layer to hold the same in proper stiff shape and to serve to reinforce 75 the same.

What is claimed is:

A shoe toe protector comprising a cap in- 80 cluding a sole portion and an upper por- tion formed integrally and of vulcanized rubber and fabric, the sole portion having a sheet of woven wire fabric, the marginal edges of the wire fabric being extended up- 85 wardly and being embedded in the lower portions of the upper portion.

In testimony whereof, I affix my signa- ture, in the presence of two witnesses.

ANTHONY L. STEBOR, JR.
